CONCRETE FORM

Silas E. Nelsen and Cyrus J. Mentzer, Tacoma, Wash.

Application January 23, 1956, Serial No. 560,495

3 Claims. (Cl. 25—131.5)

This invention relates to concrete forms.

It is the general purpose of this invention to provide a concrete form which may be used in pouring concrete to form the individual compartments making up an integrated, compartmented, concrete building such as a mausoleum. More specific objects and advantages of the present invention are the following:

(1) The provision of a concrete form which may be used in pouring a compartmented concrete building, the individual compartments of which are in exact alignment with each other, both horizontally and vertically.

(2) The provision of a concrete form which may be used in the erection of a compartmented concrete building serially until a structure of the desired size has been built.

(3) The provision of a concrete form use of which in the erection of a compartmented concrete building results in the construction of a building which is strong, braced in all directions, and resistant to earthquakes.

(4) The provision of a concrete form which when used in the erection of a compartmented concrete building produces compartments having smooth, finished inner walls without the necessity of subjecting the walls to a separate finishing operation.

(5) The provision of a concrete form the use of which results in the erection of a strong compartmented building without inclusion of space-occupying columns and beams.

(6) The provision of a concrete form which is substantially indestructible and may be used repeatedly over a long period of time.

(7) The provision of a concrete form which may be assembled and dismantled easily and rapidly and which when dismantled may be nested for easy transportation or storage in a minimum of space.

(8) The provision of a concrete form which may be used for the erection of a compartmented concrete building at an accelerated rate using a minimum crew.

The manner in which the foregoing and other objects of this invention are accomplished will be apparent from the accompanying specification and claims considered together with the drawings, wherein:

Figs. 1-5 inclusive are perspective views of the various parts of the herein described concrete form arranged substantially in their proper relationship to each other and forming in effect an exploded arrangement of the parts, Fig. 1 illustrating the front piece; Fig. 2 the back piece, Fig. 3, the bottom piece, Fig. 4 one of the two side pieces, and Fig. 5 the top piece;

Fig. 6 is a perspective view of the herein described concrete form with the component pieces assembled; and

Fig. 7 is a fragmentary view in front elevation of a compartmented building, e.g. a mausoleum, cast from concrete poured about the herein described concrete form.

Generally stated, the herein described concrete form comprises side, top, back and front pieces and means for releasably interlocking these pieces to hold them in po-

2

sition and substantially sealed against the entry of concrete poured over the assembly. A laterally expandable and retractable bottom piece also is provided. This is releasably attached to the side pieces.

- 5 A plurality of these forms may be placed in a row spaced from each other and from a back wall. Concrete may be poured over them and permitted to harden. The front and back pieces then may be removed and the bottom piece collapsed for stripping the side pieces 10 from the concrete. All of the pieces then may be disassembled, leaving a compartment forming one unit of a compartmented concrete building.

Considering the foregoing in greater detail and with particular reference to the drawings:

- 15 The bottom piece of the herein described concrete form assembly is indicated generally at 10 and illustrated in detail in Fig. 3. It includes a pair of laterally spaced apart side members or side rails 12, 14 which for the sake of stiffness preferably comprise angle irons. Fixed to the inner sides of the angle irons are sleeves 16-22 and lugs 23.

A central bar 24 having an upturned end 26 extends longitudinally centrally between side rails 12, 14 and substantially parallel thereto. It is interconnected with 25 the side rails by means of a plurality of pivotally mounted links 28.

A screw 30 is anchored rotatably into the upturned end 26 of bar 24 and also is threaded into a sleeve 32 which may be mounted on the front piece of the form assembly as will appear hereinafter. Screw 30 is substantially co-axial with center bar 24. Accordingly as it works in upturned end 26 and sleeve 32 it moves the bar in an axial direction. This in turn extends or retracts side rails 12, 14 in a lateral direction.

- 35 The side pieces 34 are releasably secured to the bottom piece 10. They may be substantially identical in construction, except that they are mirror images of each other, the one being for the left side and the other for the right. Both are comprised of metal sheets of substantial gauge. The lower portions of the sheets are substantially vertical, while the integral upper portions are arched inwardly toward, but spaced apart from, each other.

Sleeves 36, 38 are affixed to the lower inside margins 45 of the side pieces. These sleeves register with sleeves 16, 18 on the side rails of the bottom piece. Slidable therein are pins 40, 42 which consequently provide a means for aligning and releasably securing the side pieces to the bottom piece.

Means also are provided for releasably interconnecting the side pieces to the back and front pieces of the assembly. Accordingly there is provided a perforated flange 46 welded or otherwise secured to the inside back end margin of each side piece. Also, there is provided a 55 slotted tongue 48 extending outwardly from the forward edge of each of the side pieces. A peripheral rib 50 is provided on the outer end margin of each side piece for stiffness and also to form a rabbet in concrete poured over the form. This in turn creates a recess into which 60 a concrete slab or other closure may be inserted if it is desired to close off the front opening of the compartment formed by pouring concrete about the form. Extensions of ribs 50 overlie the outside face of side rails 12, 14 and cooperate with lugs 23 in preventing displacement of the side pieces when a weight of concrete is poured against them.

The opening between the spaced edges of the two side pieces and the top of the form is sealed off by means of a top piece 52. Like the side pieces, this piece may be formed to advantage of a metal sheet of substantial gauge. For stiffness it is provided with a central longitudinal rib 54. Its outer forward end margin is pro-

vided with a rib 56 which registers with ribs 50 on the side pieces and with them form a continuous rib structure which in turn results in the formation of a continuous rabbet in the concrete.

To maintain side pieces 34 properly spaced from each other even when a heavy weight of concrete is poured about the form, there are provided a pair of longitudinally extending flanges 58, 60 running the length of the inner surface of top piece 52 but set in from the edges by an amount sufficient to permit the top piece to overlap the two side pieces as required to seal off the interior of the form against entry of fluid concrete.

Means are provided on the top piece for affixing it to the back and front pieces. Accordingly there is welded to the inside rear margin of the top piece a perforated flange 62 which registers and cooperates with flanges 46 on side pieces 34 to provide a continuous member for securing a back piece to the top and side pieces. Also, a slotted tongue 64 extends outwardly from the front edge of the top piece. This is used for securing the top piece to the front piece.

Back piece 66 of the presently described concrete form also is made of heavy gauge metal and is dimensioned to overlie and close off the rear opening formed by the side pieces, top piece and bottom piece. It is provided with means for securing it to the top and side pieces. Any suitable means may be used for this purpose, for example, perforations registering with the perforations in flanges 46, 62 in the side and top pieces through which bolts may be inserted. More conveniently, however, back piece 66 may be provided with a plurality of threaded studs 68 positioned for insertion in the perforations in the flanges 46, 62 so that the back piece may be bolted thereto.

Still further, there are vertically spaced apart, aligned openings 70, 72 extending through the back plate. These are adapted for placement of inserts extending into the concrete poured behind the back plate for forming openings of predetermined size and shape.

Front piece 74 is a rigid member made up primarily of a heavy gauge metal plate cut with an opening to provide an entrance into the interior of the form. This plate is stiffened and made rigid by the presence of upper enlarged corner areas, which serve as braces, and also by a peripheral flange 75. This flange has spaced holes 76 through its side components.

The front piece preferably is substantially rectangular and is sufficiently large so that it completely overlies and extends beyond the front opening formed by side pieces 34 and top piece 52. Thus when two or more of the form assemblies are placed next to each other, with the side edges of the front pieces abutting, the front pieces may be bolted together through holes 76, leaving between the side pieces of the forms spaces having widths determined by the extent of projection of the front pieces. These may be filled with concrete and determine the thickness of the walls of the poured concrete structure. The elevation of the top of the front pieces above top piece 52 determines the depth to which the concrete is poured over the forms, and hence the thickness of the ceiling of the structure.

To fasten the front piece to the side pieces there are provided aligned slots 77, 78 on the opposite sides of the front piece. These are adapted to receive slotted projections 48 on the side pieces. Also a slot 80 is provided at the top of the front piece. This is dimensioned to receive tongue 64 on the top piece. When tongues 48, 64 are inserted in slots 77, 78, 80 wedges 82 may be driven into the slots, whereby wedging the front piece tightly against the side and top pieces.

To assist in aligning the compartments which are integrated to form the final concrete structure, front piece 74 is formed with vertically aligned openings 83, 84. Openings 83 are dimensioned to receive bolts 86 which

are embedded in the stepped floor upon which the form is placed. Openings 84 are dimensioned to receive bolts 88 (Fig. 6) which will be embedded in the concrete poured over the form and will project from the front face of the solidified concrete for entering openings 83 in the bottom of the front face of the form when the form is applied to the casting of a superimposed tier of compartments.

Means also are provided for securing the bottom piece 10 to the front piece 74. Such means in the illustrated form comprise perforated flanges on sleeve 32. These perforations register with a pair of openings 90 through the lower lip of front piece 74. Accordingly bolts 92 may be inserted through the registering openings and employed to hold the bottom piece in place during its operation.

Manner of using the form

In using the form bottom piece 10 is placed on a stepped floor in its approximate final position with side rails 12, 14 fully extended. It is spaced apart a suitable distance from a back wall, which may be the back wall of the building or the back wall of a group of previously cast compartments. Side walls 34 then are placed in position with pins 40, 42 in sleeves 36, 38 on the side walls entering registering sleeves 16-22 on the bottom piece. This leaves the top of the form open so that workmen can enter it to make adjustments.

Next, front piece 74 is placed in position. During this operation bolts 86 extending outwardly from the stepped floor on which the form is placed are inserted in perforations 83 in the bottom of the front piece. Also tongues 48 on the side pieces are inserted in slots 77, 78 on the front piece. Wedges 82 are wedged into these slots and bolts 88 are placed in openings 84.

Back piece 66 next is connected to the side pieces. This is accomplished by inserting studs 68 on the back piece into the perforations through flanges 46.

Last of all the top or cap piece 52 is placed overlapping the spaced top edges of the side pieces, flanges 58, 60 on the top piece serving as abutments and preventing collapse of the side pieces into the interior of the form. Rib 56 on the top piece is aligned with the ribs 50 on the side pieces to form a continuous rib which produces a rabbet in the concrete poured about the form. Perforated flange 62 on the top piece registers with perforated flanges 46 on the side pieces, studs 68 on the back piece being inserted through the perforations. Tongue 64 is inserted into slot 80 in the front piece and wedge 82 wedged into the slot in the tongue.

A plurality of forms may be erected in horizontal alignment with each other, spaced apart uniformly by the rims on front pieces 74 and interlocked by bolts extending through openings 76. Concrete then may be poured over the entire group, whereupon it will flow between the individual forms, between the forms and the back wall, and over the forms to a height determined by the elevation of the top surfaces of front pieces 74, thereby embedding bolts 88 which thereafter may be used for aligning another group of the forms.

After the concrete has hardened, wedges 82 are loosened and pins 40, 42 removed. Screw 30 then is adjusted to retract side rails 12, 14 and collapse bottom piece 10. Front piece 74 then may be taken off and bottom piece 10 removed. The inserts placed in openings 70, 72 through the back piece 66 may be taken out. Thereafter side pieces 34, back piece 66 and top piece 52 may be removed. This leaves an individual concrete compartment having an interior surface which is smooth and finished without being subjected to a separate finishing operation. The compartment is formed with a marginal rabbet 94, which may be used to seat a concrete slab or other closure for the front of the compartment, and with back wall openings 96, 98. Where a plurality of

the forms are used in combination with each other, a composite compartmented structure having the general appearance indicated in Fig. 7 may be built one tier at a time, the top of each finished tier acting as the floor for the next tier.

It is to be understood that the form of our invention herewith shown and described is to be considered as a preferred example of the same, and that various changes in the shape, size and arrangement of parts may be resorted to without departing from the spirit of our invention, or the scope of the subjoined claims.

Having thus described our invention, we claim:

1. A concrete form for casting a tiered, compartmented building, said form comprising an inwardly collapsible bottom member, a pair of laterally spaced unitary upwardly arched side members terminating in laterally spaced upper edges, means releasably securing the lower ends of the side members to the lateral sides of the bottom member, a unitary top member having flanged longitudinal sides arranged to overlie and abut the spaced upper edges of the side members to prevent inward collapsing of the latter, a rear wall separate from the bottom member and having a periphery not greater than the outer periphery of the side and top members, means releasably securing the rear wall to the side and top members outside the rear ends of the latter, a front wall, and means releasably securing the front wall to the bottom, side and top members.

2. The concrete form of claim 1 wherein the front wall includes side flanges disposed laterally outward from the side members, whereby a plurality of front walls may be arranged side by side with adjacent side flanges secured together for securing a plurality of forms together with the side members thereof in spaced relation to each

10

other, for pouring concrete over the plurality of forms and forming a multiple compartmented structure.

3. A concrete form for casting a tiered, compartmented building, said form comprising an inwardly collapsible bottom member, a pair of laterally spaced unitary side members including top sections, means releasably securing the lower ends of the side members to the lateral sides of the bottom member, a rear wall separate from the bottom member and having a periphery not greater than the outer periphery of the side members, means releasably securing the rear wall to the side members outside the rear ends of the latter, a front wall, and means releasably securing the front wall to the bottom and side members.
